The ornamental design for a combined fishing rod and knife, as shown and described.

DESCRIPTION

FIG. 1 is a perspective view of a combined fishing rod and knife holder showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top view thereof; and,
FIG. 7 is a bottom view thereof.
FIGS. 1, 2, 3, 4 and 5 have been broken away and bracketed to show indefinite length.

FIG. 6

FIG. 7

FIG. 1

FIG. 2

FIG. 3
